CLAIM

The ornamental design for an antenna housing for a vending machine, as shown.

DESCRIPTION

FIG. 1 is a top perspective view of an antenna housing for a vending machine showing our new design;

FIG. 2 is a front elevational view thereof;

FIG. 3 is a side elevational view thereof;

FIG. 4 is a top plan view thereof;

FIG. 5 is a bottom plan view thereof; and,

FIG. 6 is a perspective view thereof attached to a vending machine.

The broken lines are shown in the views for illustrative purposes only and form no part of the claimed design. The broken lines showing the vending machine in FIG. 6 are included for the purpose of illustrating environmental structure only and form no part of the claimed design.
